[57] CLAIM

The ornamental design for an interrogation gate for an electronic article surveillance system, as shown.

DESCRIPTION

FIG. 1 is a perspective view of an interrogation gate for an electronic article surveillance system showing our new design;

FIG. 2 is a front elevational view thereof;

FIG. 3 is an end elevational view thereof;

FIG. 4 is a top plan view thereof;

FIG. 5 is a bottom plan view thereof; and

FIG. 6 is a fragmentary cross-sectional view taken along lines 6—6 of FIG. 3.

FIG. 1

FIG. 3

FIG. 2

FIG. 4
